UNITED STATES PATENT OFFICE.

ROBERT C. GROH, OF ST. PAUL, MINNESOTA.

DESIGN FOR A STOCKING.

Application filed February 10, 1923. Serial No. 5,135. Term of patent 7 years.

To all whom it may concern:

Be it known that I, ROBERT C. GROH, a citizen of the United States, residing at St. Paul, in the county of Ramsey and State of Minnesota, have invented a new, original, and ornamental Design for Stocking, of which the following is a specification, reference being had to the accompanying drawing, forming part thereof.

The figure is a view of a stocking showing my new design.

I claim:

The ornamental design for a stocking, as shown.

ROBERT C. GROH.
